THEIR ATTY.

UNITED STATES PATENT OFFICE.

HENRY THOMSON, OF PERTH, WESTERN AUSTRALIA, AUSTRALIA, AND WILLIAM R. OYSTON, OF KENSINGTON, NEAR SYDNEY, NEW SOUTH WALES, AUSTRALIA; SAID OYSTON ASSIGNOR TO SAID THOMSON.

AUTOMATIC MUSIC-SHEET TRACKING DEVICE FOR PLAYER PIANOS AND OTHER INSTRUMENTS.

Application filed November 18, 1920. Serial No. 424,812.

To all whom it may concern:

Be it known that we, HENRY THOMSON, residing at Perth, in the State of Western Australia, Commonwealth of Australia, and 5 WILLIAM ROBERT OYSTON, residing at Kensington, near Sydney, in the State of New South Wales, Commonwealth of Australia, both subjects of the King of Great Britain, have invented new and useful Improvements 10 in Automatic Music-Sheet Tracking Devices for Player Pianos and other Instruments, of which the following is a specification.

This invention relates to an improved music-sheet tracking device for player- 15 pianos and other musical instruments, and it has been devised in order to provide a tracking device of simple mechanical construction, which is automatic in its operation and is controlled directly by the music-sheet it- 20 self in its travel over the tracker-bar of the instrument.

For the purpose of maintaining a perforated music-sheet in correct playing relationship to the tracker-bar and its air-ducts, it 25 is customary to provide in player-pianos either adjustment devices which are not wholly effective in their action, or automatic adjustment means which are of a complex mechanical and pneumatically operated character and indirect in action.

The present invention is characterized by the provision of frictional members or spool flanges adapted to bear against the edges of the music-sheet; means automatically causing 30 the approach of said members to the music-sheet edges during the forward motion of the sheet; means automatically maintaining said members in fixed relative positions whilst the music sheet is travelling truly; and means for automatically moving 35 said members outwardly during the rewinding of the music-sheet.

Reference is made to the accompanying drawings, wherein:

45 Figure 1 is a view in front elevation illustrating a preferred embodiment of the invention.

Figure 2 is an end elevation illustrating a braking device, and

50 Figure 3 is a view in plan illustrating a constructional modification.

In these views, the letter A designates a portion of the spool-propelling mechanism

embodied in a player-piano; B the end walls of a spool-casing; C the tracker-bar; D the 55 music-roll holder devices; E the revolvably mounted take-up spool, and F the clip fastening for engagement by the ring provided at the commencement of the perforated music-sheet. These parts are all as ordinarily employed in player-pianos and they 60 may be of any approved standard construction and arrangement.

According to the invention the take-up spool E is fitted at its opposite ends with 65 spindles a and b, one of which is screwed with a left hand thread and the other with a right-hand thread.

On each of the screwed spindles a and b there is loosely mounted a guide disc c, preferably of aluminium, having a centrally positioned boss d which is internally threaded to form a screw engagement with its spindle.

Inwardly extending arms e are fitted to the end walls B of the spool-casing, and fixedly mounted on said arms are check-members which may be in the form of flat springs f having at their free outer ends braking pads g of leather or like suitable material. These braking pads bear constantly upon 80 the bosses d of the guide discs c.

In action, the end ring of the rolled music-sheet is hooked to the take-up spool E, and rotary motion is imparted to the latter by the operation of the motor A in the usual 85 way.

Owing to the braking action of the spring controlled pads g, the guide discs c do not at first rotate with the spool E and are, therefore, caused by reason of the action of the 90 screw-threads of the spindles a and b to approach towards each other and the opposite edges of the music-sheet. The pitch of the screw-threads is such that the spool completes several revolutions before said guide 95 discs come into contact with the edges of the music-sheet.

When the guide discs c do contact with the edges of the music-sheet, the pressure exerted by frictional contact is sufficient to 100 overcome the braking action of the pads g controlled by the weak springs f, whereupon the discs revolve with the spool E and function as efficient guides for the maintenance of the music-sheet in correct playing position.

When the spool E is rotated in the reverse or rewinding direction by means of power transmitted from the motor A, the guide discs c travel outwardly on their respective spindles, and the amount of such outward travel is limited by their contact with the inner edges of the flat springs f.

According to the modification illustrated in Figure 3, the braking pads g are fitted to the inner ends of springs f' suitably anchored to the side walls B of the spool-casing, and said pads bear against the faces of the loosely mounted guide discs c. Other modifications may be made within the scope of the invention. For example, there may be employed retarding weights which are adjustable and applicable in a variety of ways, in lieu of the spring sustained braking pads herein described.

20 What we do claim is:—

1. In perforated sheet controlled mechanism, a take up spool for said sheet having spindles at opposite ends to rotatably support the same, guide members mounted on said spindles to have movement toward and away from said spool and rotate with the spool, means to hold said guide members against rotation and cause the same to be moved inwardly on the spindles in a direction toward each other to contact with the edges of the sheet as the sheet is wound upon the take up spool, to maintain said guide members in fixed position on the spindles relative to the sheet and rotate with the take up spool when the sheet is travelling true, and to cause said guide members to move outward on said spindles in a direction from each other and away from the edges of the sheet during the unwinding of the sheet 40 from the take up spool.

2. In perforated sheet controlled mechanism, a take up spool having spindles at opposite ends to rotatably support the same, one of said spools being arranged with a right hand screw thread and the other with a left hand screw thread; guide flanges mounted on said spindles in threaded connection therewith; yielding means to retard

the movement of said flanges with said spindles and cause the flanges to be moved on the spindles in a direction toward each other as the sheet is wound upon the take up spool to bring said flanges into contact with the edges of the sheet, said contact of the flanges of the sheet adapted to overcome the flange retarding means, and said retarding means adapted to retard the movement of said flanges as the sheet is unwound from the take up spool for the purpose specified.

3. Tracking means for perforated music-sheets comprising a take-up roll, spindles on said roll arranged with left and right-handed screw-threads, roller flanges adjustably mounted on said spindles, and check members acting on said flanges. 60

4. Tracking means for perforated music-sheets comprising a take-up roll having spindles arranged with left and right-handed screw-threads, guides having a screw threaded engagement with said spindles, and 70 braking pads acting on said guides.

5. Tracking means for perforated music-sheets comprising a take-up roll having spindles arranged with left and right-handed screw-threads, guide flanges on said spindles, internally threaded bosses on said flanges in threaded connection with the spindles and spring-controlled braking pads bearing on said bosses. 75

6. In perforated sheet controlled mechanism, a take up spool having spindles at opposite ends to rotatably support the same, one of said spindles being arranged with a right hand screw thread and the other with a left hand screw thread; guide flanges 85 mounted on said spindles in threaded connection therewith; springs carrying pads to cooperate with said guide flanges; and means to rotate the take up spool.

In testimony whereof we affix our signatures in presence of two witnesses.

HENRY THOMSON.
WILLIAM R. OYSTON.
